UNITED STATES PATENT OFFICE.

GEORGE FRANÇOIS JAUBERT, OF PARIS, FRANCE.

CARTRIDGE FOR THE PREPARATION OF OXYGEN.

1,025,191.

Specification of Letters Patent.

Patented May 7, 1912.

Application filed November 10, 1909. Serial No. 527,178.

To all whom it may concern:

Be it known that I, GEORGE FRANÇOIS JAUBERT, a citizen of the Swiss Republic, residing 155 Boulevard Malesherbes, Paris, France, have invented new and useful Improvements in Cartridges for the Preparation of Oxygen, of which the following is a specification.

This invention relates to the preparation of oxygen, or gaseous mixtures rich in oxygen, by the auto-combustion of pulverulent mixtures composed of chlorates, perchlorates, nitrates, etc., mixed with substances capable of maintaining combustion, such as carbon. It has been recognized that it is impossible to burn large quantities of such mixtures in a closed vessel because their combustion is defective and produces an increase of swelling of the mass; and it has been found that the combustion of such mixtures could be successfully brought about by confining relatively small masses within containers which permit the lateral escape of the resulting gases through the mass, and to this end the combustion of these substances has been carried out inside an incombustible envelop capable of allowing the gases produced to escape laterally, which envelops have been composed of asbestos fabric, for example. Such asbestos envelops are not suitable for transportation of the pulverulent mixtures and are not easily handled at the moment of their employment. Perforated metallic cartridges containing the pulverulent mixture and suitable for introduction into a generating apparatus have also been employed, but such cartridges have heretofore always been lined with an asbestos fabric to prevent the burning of the metal by the combustion of the mass, which takes place in the presence of oxygen under pressure.

I have discovered that the combustion of the materials for the liberation of oxygen may be brought about directly inside of an unperforated metal envelop, of iron, for example, without the interposition of an insulating body, so that the cartridge or envelop may be utilized for package and transportation of the mixture and also may be utilized as the receptacle for the mixture during combustion, a manipulation of the chemical substances prior to their employment being thus obviated and the manufacture of the cartridge rendered more economical.

An embodiment of the invention is represented in the drawing which shows a cartridge constituted by a box *a* of tinned sheet iron, for example, formed by a cylindrical body lapped, but not soldered along a line or seam *b*, and which may conveniently have at its lower end a flange *c* upon which rests a perforated plate *d*. The cartridge is completed and closed, to serve as a receptacle for transport, by a removable bottom cover *e* and a top cover *f*, which fit onto the ends of the cylindrical body. In packing the cartridge the perforated plate *d* and the removable bottom cover *e* are arranged in place and the receptacle is filled with the pulverulent mixture. When the cartridge is full the cover *f* is put on and the cartridge is then ready to be shipped.

In order to utilize this cartridge in the combustion of the mixture to produce oxygen its two covers are removed and it is introduced into an appropriate generating apparatus and the charge is kindled in the ordinary way. The combustion is propagated throughout the entire mass, in the same manner as in the old asbestos containers, the oxygen escaping through the mass to the walls of the cartridge and through the open ends thereof, and in accordance with my discovery the outer walls of the cartridge will be protected and prevented from being consumed even under the high temperature of combustion of the mass (about 1000° centigrade) and in the presence of oxygen under pressure.

The advantages are as follows: The invention permits the utilization, for the manufacture of cartridges, of metals of all kinds as thin as may be desired—for example, sheet iron, tin, copper or aluminium, without the interposition of an incombustible insulating body such as asbestos fabric, so that the manufacture of the cartridges is rendered more rapid and more economical; and the cartridges may be used both for the shipment and for the combustion of the mixture, whereby manipulation of the chemical substance at the moment of the preparation of the oxygen is avoided.

While I prefer to employ the perforated plate *d* at the lower end of the cartridge, this is not essential to my invention and may be omitted.

What I claim is:—

1. A cartridge for the preparation of oxygen or gaseous mixtures rich in oxygen com-

110

prising an envelop made of a combustible metal and filled with a pulverulent mixture containing a combustible substance and a substance substantially as described which 5 when heated will give off oxygen to unite with the combustible substance and an excess of free oxygen, said pulverulent mixture being in direct contact with the metallic envelop, and said envelop having removable end covers, whereby the envelop serves for the transportation of the mixture and also as a container during combustion. 10 2. A cartridge for the preparation of oxygen or gaseous mixtures rich in oxygen comprising an envelop made of a combustible metal and filled with a pulverulent mixture containing combustible substance and a substance substantially as described which 15 when heated will give off oxygen to unite with the combustible substance and an excess of free oxygen, said pulverulent mixture being in direct contact with the metallic envelop, said envelop having removable end 20

covers and a perforated plate in its lower end, whereby the envelop serves for the 25 transportation of the mixture and also as a container during combustion.

3. A cartridge for the preparation of oxygen or gaseous mixtures rich in oxygen comprising an envelop made of a combustible metal and filled with a pulverulent mixture containing combustible substance and a substance substantially as described which 30 when heated will give off oxygen to unite with the combustible substance and an excess of free oxygen, said pulverulent mixture being in direct contact with the metallic envelop. 35

In witness whereof I have hereunto placed my hand, at Paris, France, this 28th day of 40 October 1909.

GEORGE FRANÇOIS JAUBERT.
